UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DUMP-CAR.

1,076,591

Specification of Letters Patent

Patented Oct. 14, 1913.

Application filed December 6, 1911. Serial No. 694,291.

To all whom it may concern:

Be it known that I, ARGYLE CAMPBELL, a citizen of the United States, residing at Chicago, in the county of Cook and State of Illinois, have invented a certain new and useful Improvement in Dump-Cars, of which the following is a full, clear, concise, and exact description, reference being had to the accompanying drawings, forming a part of this specification.

My invention relates to improvements in railway car construction.

The object of my invention is to provide a railway car of comparatively cheap and light construction, and yet of great strength, and one capable of enduring the severe shocks of service.

Certain features of my invention herein have been divided out and form the subject matter of divisional applications, respectively Serial No. 720,149, and Serial No. 720,150, filed September 13, 1912. In my application herein I confine my claims to the hopper structure, whereas in my pending applications the claims are particularly directed to the underframing of a car and to other features relating to car construction.

The means that I employ to practically accomplish this object may be used in connection with different forms of railway cars, and I propose to describe specifically one form of car embodying the elements of my invention, and have chosen for such description a car commonly known as a "ballast car," though it will be understood that by making this specific description in connection with a car of this type I do not intend to be limited thereto, as it will be readily apparent that the broad principles of my invention are readily applicable to many types of railroad cars.

Referring to the drawings Figure 1 is a side elevation of substantially one-half of a railroad car embodying my invention, Fig. 2 is a plan view of the same, Fig. 3 is a cross section taken on line 3, 3 of Fig. 2, Fig. 4 is a cross section taken longitudinally of the car of the transverse hopper at line 4, 4, of Fig. 2, and showing the method of attaching the hopper doors and hinge butts.

Referring to the drawings 10 is a car body, 11 the side of the car, 12 a hopper bottom, 13 the end floor of the car, 14 the end of a car, 15 the end sill of a car, 16

the central longitudinal hopper sheet, 17 a transverse hopper sheet, 18 the car doors, 19 the car door in its open position.

19 is a pivot attachment of the door mechanism to the door 18.

20 are connecting rods which are used for operating the car doors 18 in connection with the lever 21 borne upon the shaft 22, which is journaled in suitable bearings 23, and operated by ratchet 24.

25 are door hinges rigidly attached by suitable means at the upper edges of the door 18. The said hinges have an angle or turn so that the blade of the hinge is substantially at right angles with the door 18.

Each door opening adapted to be closed by a door 18 has adjacent each side one of the transverse hopper sheets 17, each transverse hopper sheet being substantially at right angles to the upper edge of the door 18, which door is adapted to swing transversely of the car. The hinges 25, there being preferably one at either end of the upper edge of each door 18, are attached to the transverse hopper sheets, preferably on the outer face 45 thereof with reference to the adjacent door opening. In preferable construction a hinge butt 27 is employed for such attachment, the same being secured to the transverse hopper sheet by the rivets 28, 28, and the hinge being pivoted to the hinge butt by means of the pin 26. By means of the angle provided in the hinge and by reason of the attachment of the hinges to the transverse hopper sheets I am enabled to provide a door which upon opening in discharging the load tends in its opening movement to elevate and allow the distribution of the discharging load toward the center of the track.

29 is a single center sill extending longitudinally of the car with its ends passing preferably to the forward edges of the body bolster 30 of the car, though the same may be extended to the draft devices, and having a vertical recess 31 on its under surface for the reception of the king pin not shown in the drawings.

39 are angle irons vertically disposed at the inner ends of the end floor of the car forming the slots 40 for the reception of partitioning means between the level and the hopper portion of the car. To provide a convenient space for the keeping of said partitioning means when it is desired to use

the entire car in service for the carrying of a commodity I have provided a means at the ends of the car by forming the slots 41 between the end 14 of the car and the vertically arranged angle irons 42, which are attached by suitable means to the sides of the car, as illustrated in Fig. 2.

I have thus described the application of my invention to one type of car.

19 I claim:

1. In a dump car, the combination of a hopper having longitudinal and transverse hopper sheets, car doors associated therewith adapted to swing transversely of the car, and provided with door operating mechanism, of angular hinges secured to each door and pivoted to the transverse hopper sheets.

2. In a dump car, the combination of a hopper having longitudinal and transverse hopper sheets with hopper doors associated therewith, said doors being provided with door operating mechanism adapted to swing the same transversely of the car, and each attached to the hopper by angular hinges pivoted to the transverse hopper sheets, whereby uniform central distribution of the load from the car is secured.

3. In a dump car, the combination of a hopper having longitudinal and transverse hopper sheets, hopper doors associated with

said hopper, and provided with door operating mechanism adapted to swing said doors transversely of the car, each of said doors being attached to angular hinges, each of said hinges being pivoted to the transverse hopper sheets, whereby the said doors upon opening tend to elevate and centrally distribute the load of the car.

4. In a dump car, the combination of a hopper with openings between longitudinal and transverse hopper sheets, with hopper doors arranged longitudinally of the car, each of said doors associated with door operating mechanism, and each provided with hinges having blades substantially at right angles with the door, the said hinges being pivoted to the transverse hopper sheets, whereby upon opening the said doors elevate and centrally distribute the load.

5. In a dump car, the combination of a car body having a door opening, longitudinal and transverse hopper sheets forming said opening, a door therefor, hinges connected to the door, and hinge butts to which the hinges are pivoted, the hinge butts being secured to the transverse hopper sheets.

ARGYLE CAMPBELL.
